UNITED STATES PATENT OFFICE.

THOMAS R. BROWN, OF SPARKILL, NEW YORK, ASSIGNOR TO THE WESTINGHOUSE AIR BRAKE COMPANY, OF WILMERDING, PENNSYLVANIA, A CORPORATION OF PENNSYLVANIA.

AUTOMATIC ELECTRIC TRAIN-LINE COUPLING.

1,199,866.

Specification of Letters Patent.

Patented Oct. 3, 1916.

Application filed March 31, 1914. Serial No. 828,466.

To all whom it may concern:

Be it known that I, THOMAS R. BROWN, a citizen of the United States, and a resident of Sparkill, in the county of Rockland and State of New York, have invented a certain new and useful Improvement in Automatic Electric Train-Line Couplings, of which improvement the following is a specification.

This invention relates to mechanism for automatically coupling the electric train line circuits between the cars or other vehicles of a train, and more particularly to that type of electric coupler in which each counterpart coupling head is provided with a plurality of fixed contacts or fingers connected to the respective train line circuits, and a movable contact carrier, one of said carriers being adapted to be projected from one coupler head to the other and electrically connect the corresponding contact fingers of the two couplers when the same come together.

The principal object of my present invention is to provide an improved coupling device of this type, and in which the operation of the moving parts is determined by the action of springs and other mechanical connections operating automatically upon the coming together of the counter-part couplers of adjacent cars to project one of said carriers.

Another object is to provide improved mechanism for automatically opening and closing the doors or shutters controlling the opening at the front end of the coupler casing, through which the contact carriers or slides are projected; and still another object is to provide improved fluid pressure means for releasing the couplers and restoring the parts to normal position.

In the accompanying drawings: Figure 1 is a horizontal section of a coupler head, embodying my improvement; Fig. 2 a longitudinal vertical section taken on the line 2-2 of Fig. 1; Fig. 3, a transverse section taken on the line 3-3 of Fig. 1; Fig. 4, a transverse section near the front end of the coupler and showing the doors or shutters in elevation; Fig. 5, a detail view showing one of the rings and arms for operating the shutters; Fig. 6, a detail view of the end of the plunger and the surrounding bushing on which the rings are mounted; and Fig. 7, a diagrammatic view, partly in plan and

partly in section, showing a pair of couplers connected together, and illustrating a modification.

As shown in the drawings, the electric coupling device comprises a casing, 41, which may be suspended beneath the draw bar, car coupler, or other support at the end of the car in such position as to engage a counterpart coupling device on an adjacent car, and is particularly adapted for use in connection with a car coupler of the so-called rigid lock type, such as indicated in Fig. 7, for instance, in which each counterpart coupler head, 12, is provided with a hook shaped projection, 14, having a vertical plane surface inclined at an angle to the line of draft, and adapted to engage and interlock with a corresponding surface on the projection of a counterpart coupler by relative lateral movement when said couplers come together in the act of coupling. Each coupler head is also provided with a pivoted lock, 16, adapted to bear against a locking surface, 17, on the outer side of the projection, 14, of the counterpart coupler, and hold the couplers securely clamped together when in coupled position.

For the purpose of releasing the lock of the coupler, fluid pressure means are provided, comprising a cylindrical chamber 85 formed in the coupler head and containing a piston, 18, which is connected by a rod, 19, with an arm of the pivoted lock, 16, a spring, 20, acting on the back of the piston to normally hold the lock in its locking position. Fluid under pressure, such as compressed air, may be admitted to the cylinder for actuating the piston, 18, to compress the spring and turn the pivoted lock, 16, to its releasing position when it is desired to uncouple and separate the couplers. Such a construction is set forth in the prior application of James S. Doyle and Frank Hedley, filed March 24, 1913, Serial No. 756,469.

The casing, 41, containing the electric contact devices may be supported beneath the coupler head in any convenient manner, as by means of bolts, 69, at or near the outer end, and link, 65, and spring, 67, at the middle of the rear portion, in such position that the adjacent ends of the two casings of the counterpart couplers meet together when coupled. In the casing, 41, are mounted a plurality of contact fingers, 43, preferably

in a horizontal row, or a double row one above the other as shown in Fig. 2, near the outer end of the casing, and each connected with a corresponding wire of the train line circuits. Other sets of contact fingers, 45, may be employed for closing certain local circuits upon each car when in uncoupled position. In order to establish electrical connection between the respective contact fingers of the counterpart couplers, there is a sliding contact carrier, 46, mounted in the casing and having a plurality of sets of contact bars, 47 and 48, properly connected and adapted to engage the sets of contact fingers, 43, of the adjacent counterpart couplers when coupled together with one of the slides extended into the casing of the other coupler, whereby the contacts of the movable carrier bridge over the space between the said sets of contact fingers, as indicated in Fig. 7, and establish the desired electrical connection. The contact bars, 47 and 48, at one side of the center line are preferably cross connected with the corresponding contact bars on the opposite side of the center line.

According to one feature of my improvement, the contact carriers or slides are operated automatically by mechanical means when the couplings are brought together, and for this purpose each coupling is provided with a spring pressed plunger or tappet, 38, slidably mounted within the fixed bushing, 40, located in the middle portion of the casing, the plunger being tubular at its rear portion, and containing the spring, 35, which acts to normally extend the end of the plunger beyond the front face of the casing, and in position to be engaged by the corresponding plunger of a counterpart coupling of an adjacent car. A mechanical trip mechanism is employed between the yielding plunger and the slide for actuating the same, and as shown in Figs. 1, 2, and 3, this mechanism comprises a horizontal sector gear, 27, pivoted upon the pin, 28, within the casing, and carrying a pivot pin, 34, on which is pivoted a toggle arm, 29, provided with a T head, 30, bearing against the follower, 31, of the spring, 35, the pivot of the toggle arm, 29, being normally in line with the pin, 28, and the axis of the spring, 35, and plunger, 38, when the parts are set in position for coupling. The sector gear, 27, meshes with the small pinion, 44, carried by the larger pinion, 49, which engages the rack, 50, on the flange, 51, of the slide or contact carrier, 46, which is mounted upon the rollers or balls, 58, supported on the flanges, 42, of the casing. The projections at opposite sides of the head, 30, of the toggle arm, 29, extend into the respective slots, 31 and 32, in the tubular plunger, 38, and one of said projections is adapted to be engaged by the

plunger at the end of the slot when the plunger is forced inwardly to a certain point.

When the two counterpart couplings are brought together in the act of coupling, the outer ends of the two plungers abut against each other, and both are forced inwardly compressing the springs, 35. As the springs and the friction of the parts is never exactly the same in any two couplers, it follows that one of the plungers will be forced inwardly a sufficient distance to engage the head of its toggle lever and trip the same slightly before the other plunger, and as the compression of the spring is exerted in line with the toggle arm and pivot pins, 34 and 28, there is no movement of the gears until the toggle lever is tilted by contact with the plunger at the end of slot, 32. This operates to throw the pivot, 34, inward and out of line with the pivot, 28, whereupon the spring acts with increasing leverage to turn the sector gear, 27, upon its pivot, and through the connecting gears, 44, 49 and 50, project the slide, 46, through the open front end of the casing and into the casing of the other coupler where it abuts against the corresponding slide and moves the same backward to the rear position. As soon as the slide begins its backward movement, the pivot of its toggle arm will be thrown out of line, and its spring, which is at that time under compression, will then assist in the further backward movement of the slide. In this way, the slides are thrown with a quick positive movement to the coupled up portion in which the contact fingers, 43, in one casing, engage the contacts, 47, on the slide, and the contact fingers in the other casing engage the contacts, 48, on the slide, thereby establishing through connections for the respective train line circuits. For the purpose of cushioning this movement of the slides, a piston or plunger, 52, may be mounted on the slide, 46, and operate in a cylinder, 53, formed within the casing, and having a small port, 54, at its inner end. As the piston moves toward the end of the cylinder it compresses the air therein, thus exerting a yielding resistance to the movement of the slide at the end of its stroke.

In order to release the coupling and withdraw the slide, I provide a piston, 24, having a stem, 26, adapted to bear against the sector gear, 27, and turn the same back to the normal release position shown in Fig. 1, when fluid pressure is admitted to the face of the piston. A spring, 25, returns the piston, 24, to its normal position when the fluid pressure is released. It is desirable that the slide should be withdrawn before the couplers are separated, and this is insured by having the piston, 24, control the port, 23, leading to the cylinder of the un-

locking piston, 18, of the coupler in such a manner that when fluid, such as compressed air, is admitted to the connection, 21, and passage, 22, the piston, 24, moves out to 5 actuate the sector gear, 28, and reset the same in its normal position, and thereby withdraw the projected slide within its respective casing. At the end of its movement, the piston uncovers the port or 10 sage, 23, thereby admitting fluid therethrough to the unlocking piston, 18, to release the coupler and permit the separation of the cars. In order that the devices for withdrawing the slide and releasing the 15 couplers may be operated from either car, the passage, 22, may communicate with the corresponding passage in the other coupler by means of connecting ports, 39, formed in the heads of the abutting plungers, 38.

20 Various forms of mechanical connections between the plungers and the contact carriers may be employed. According to the modification shown diagrammatically in Fig. 7, the toggle arm, 29, is pivoted to long 25 lever, 27^a, mounted at one end on fixed fulcrum, 28^a, and connected at its opposite end to the contact carrier, or slide, 46, by means of a link, 27^b. In this construction, the piston, 24^a, has a hollow rod 24^b cooperating 30 with the push bar, 26^a, connected to the lever, 27^a, for withdrawing the slide. Except for the lever and link connection in lieu of the sector gear, pinion and rack connection, this modification is similar in construction and operation to that of Figs. 1, 2, 35 and 3, already described, and will be readily understood.

Another feature of my improvement relates to the doors or shutters for covering 40 the opening at the front of the casing, when the slide is withdrawn within the casing, for the purpose of excluding dust, dirt, and moisture. As shown in the drawings, I provide vertically sliding doors, 59 and 60, 45 adapted to meet together upon a horizontal line at about the middle of said opening when in closed position, and to slide vertically in opposite directions when moving to the open position. For the purpose of 50 operating said doors automatically at the times of the coming together and of separation of the counterpart couplers, various forms of mechanism controlled by the reciprocating movement of the plungers may 55 be employed, but a preferred construction comprises a pair of rings or yokes, 61 and 62, mounted to oscillate on the bushing, 40, and having the oppositely extending arms, 61^a, and 61^b, and 62^a and 62^b, respectively, 60 connected at their outer ends with the respective doors, 59 and 60, the shorter arms, 61^a and 62^a, being connected to the upper door, 59, by pin and slot connections, and the longer arms, 61^b and 62^b, being connected by the respective links or hangers, 35

63^a and 63^b, with the lower door, 60. The yokes or rings, 61 and 62, are provided with the respective pins or projections, 61^c and 62^c, extending through the vertical slots, 61^d and 62^d, in the bushing, 40, and into the diagonal slots, 61^e and 62^e, respectively, formed in the plunger, 38. As the slots, 61^d and 62^d, are formed in planes at right angles to the axis of the plunger, while the slots, 61^e and 62^e, are diagonal or inclined, as 70 shown particularly in Fig. 6, it will be seen that the reciprocating movements of the plunger within the bushing, will cause the yokes to oscillate upon the bushing in such a manner as to slide the doors vertically to 75 and from each other in closing and opening.

By means of this construction, the operation of the doors is entirely automatic, since, when the couplers are brought together and both plungers are forced inwardly compressing both springs, this movement operates through the slots and yokes to raise the upper door and lower the bottom door thus opening the apertures in both casings for the projection of the slide, 46, to connect 80 up the electric train line circuits as before described. Then when the couplers are released and pulled apart, the springs, 35, return the plungers to the normal outer position thereby again oscillating the yokes, 95 and moving the doors to closed position. If desired, an additional tension spring, 55, attached to the arms, 61^a and 62^a, may be employed for assisting in the closing action.

A shield or plate, 56, may be supported 100 within the casing beneath the gears, to prevent oil or other lubricant from falling upon the contact carrier, and the shield may be formed to discharge oil at its side edges upon the ball bearings, 58, of the slide. 105

Having now described my invention, what I claim as new and desire to secure by Letters Patent is:

1. In a coupling, the combination of a 110 casing containing a plurality of fixed contacts adapted to be connected to train line circuits, a movable carrier having corresponding contact bars, a mechanical trip mechanism for projecting said carrier to electrically connect the corresponding contacts of counterpart couplings, and means operating automatically by the coming together of said couplings to actuate said trip mechanism. 115

2. In a coupling, the combination of a 120 casing containing a plurality of fixed contacts adapted to be connected to train line circuits, a movable carrier having corresponding contact bars, a mechanical trip mechanism for projecting said carrier to electrically connect the corresponding contacts of counterpart couplings, and a yielding plunger adapted to engage a corresponding plunger of a counterpart coupling, for actuating said trip mechanism. 125

3. In a coupling, the combination of a casing containing a plurality of fixed contacts adapted to be connected to train line circuits, a movable carrier having corresponding contact bars, a spring-actuated plunger adapted to engage a corresponding plunger of a counterpart coupling, and a mechanical connection operated by said plunger for projecting said carrier to electrically connect the corresponding contacts of the counterpart couplings.
4. In a coupling, the combination of a casing containing a plurality of fixed contacts adapted to be connected to train line circuits, a movable carrier having corresponding contact bars, a yielding plunger, a spring acting on said plunger, a toggle arm also acted upon by said spring, means operated by the movement of the plunger for tripping said toggle arm, and mechanism actuated thereby for projecting said carrier to electrically connect the corresponding contacts of the counterpart couplings.
5. In a coupling, the combination of a casing containing a plurality of fixed contacts adapted to be connected to train line circuits, a movable carrier having corresponding contact bars, a yielding plunger, a spring acting on said plunger, a toggle arm also acted upon by said spring, means operated by the movement of the plunger for tripping said toggle arm, and gearing actuated by said toggle arm for projecting said carrier.
6. In a coupling, the combination of a casing containing a plurality of fixed contacts adapted to be connected to train line circuits, a movable carrier having corresponding contact bars, a mechanical trip mechanism for projecting said carrier to electrically connect the corresponding contacts of counterpart couplings, and means for resetting said trip mechanism and withdrawing said carrier.
7. In a coupling, the combination of a casing containing a plurality of fixed contacts adapted to be connected to train line circuits, a movable carrier having corresponding contact bars, a mechanical trip mechanism for projecting said carrier to electrically connect the corresponding contacts of counterpart couplings, a yielding plunger for actuating said trip mechanism, and a fluid pressure device for withdrawing said carrier.
8. In a coupling, the combination of a casing containing a plurality of fixed contacts adapted to be connected to train line circuits, a movable carrier having corresponding contact bars, a mechanical trip mechanism for projecting said carrier to electrically connect the corresponding contacts of counterpart couplings, and a fluid pressure operated piston for withdrawing said carrier and resetting said trip mechanism.
9. In a coupling, the combination of a coupler head, a movable lock, a fluid pressure device for releasing said lock, electrical contacts adapted to be connected to train line circuits, a movable carrier having corresponding contact bars, means for projecting said carrier to electrically connect corresponding contacts of counterpart couplers, a fluid pressure operated piston for withdrawing said carrier, and a port controlled by said piston for supplying fluid to the unlatching device of the coupler.
10. In a coupling, the combination of a casing having an opening and containing electrical contacts connected to train line circuits, a movable carrier having corresponding contact bars, mechanism for projecting said carrier through said opening to electrically connect corresponding contacts of counterpart couplers, a yielding plunger for actuating said mechanism, a door for said opening, and means operated by the movement of said plunger for actuating said door.
11. In a coupling, the combination of a casing having an opening and containing electrical contacts adapted to be connected to train line circuits, a movable carrier having corresponding contact bars, mechanism for projecting said carrier through said opening to electrically connect corresponding contacts of counterpart couplers, a yielding plunger for actuating said mechanism, a door for said opening, a yoke for operating said door, and means operated by the movement of said plunger for oscillating said yoke.
12. In a coupling, the combination of a casing having an opening and containing electrical contacts adapted to be connected to train line circuits, a movable carrier having corresponding contact bars, mechanism for projecting said carrier through said opening to electrically connect corresponding contacts of counterpart couplers, a yielding plunger for actuating said mechanism, a pair of vertically movable doors for said opening, a pair of yokes mounted to oscillate and connected to said doors, and means operated by the movement of said plunger for oscillating said yokes.
